UNITED STATES PATENT OFFICE

ALBERT HUGUENIN, OF PARIS, FRANCE

DEVICE FOR THE COOLING OF COMPRESSORS WITH PISTONS

Application filed September 14, 1926, Serial No. 135,460, and in France November 6, 1925.

The cooling means for compressing engines or machines with pistons are to-day divided into two distinct kinds:

- 1st—A jacketing of the cylinders.
- 5 2nd—Intermediate coolers between the different levels or stages in the case of compressing machines with several stages. In the case of a one-stage compressing machine, an after cooler is provided or not at the outlet 10 of the single stage, according to the use to which the compressed gas is to be adapted.

According to the present invention a box is provided on the cylinder with compression piston, two pipes connect said box respectively with the inlet and the outlet of a cooler and means are provided to open the communication of the box with the outlet of the cooler at the end of the exhaust stroke and during the admission stroke, and to produce, 15 at the end of a certain time after the beginning of the admission stroke, the closing of an exhaust valve adapted to connect the cylinder with the box. Use can be made of a cylindrical slide-valve sliding in a cylindrical box and of exciting means sending exciting currents in electro-magnetic devices enclosed within said box so as to move the slide valve at the end of every piston stroke and to open the exhaust valve during the last part 20 of the exhaust stroke and the first part of the admission stroke.

The present invention proceeds in an entirely different manner for the cylinder cooling. This process will be described with reference to the accompanying drawings given by way of example.

- 35 Fig. 1 shows a pressure-volume diagram drawn, for instance, for a three-stage compressor, and,
- 40 Fig. 2 shows the entropic diagram of the cycle of one stage.

Fig. 3 is a diagram of a compressor operating according to the new process.

- 45 Fig. 3a is a detailed section of a suction valve.

Fig. 4 is a diagrammatic elevation showing endwise the driving mechanism which is situated on the right at the bottom of Fig. 3.

- 50 Fig. 5 is a diagram of a mechanism provided with eccentrics.

Fig. 6 shows four different positions of an eccentric and a lever.

Fig. 7 indicates different curves described by one point of the lever.

Fig. 8 is a vertical section showing some 55 details of a valve and of a delivery slide-valve.

Figs. 8a and 8b are longitudinal and cross sections of the insulators through the cover.

Fig. 9 is a horizontal section made accord- 60 ing to the broken line 9—9 of Fig. 8.

Figs. 10, 11 and 12 are diagrams showing the representative curves of the slide-valve motions, of the exhaust valve and of the suction valve of one of the cylinders of the compressor, the ordinates being proportional to the vertical displacements of these parts and the abscissas being proportional to the times. 65

The parts of the diagram drawn in full lines in Fig. 1 show the normal cycles of the 70 three stages of the compressor, taking into account an intensive intermediate cooling, as it is normally used nowadays, no supplementary explanation appearing as being necessary relatively to the same. 75

The part of said diagram which is covered with hatchings in full lines shows the expansion work supplied from the gases retained in the clearance spaces of the different cylinders, which work is, by the way, completely lost to-day because the imperfect expansion does not succeed in reaching the full temperature fall of the gases at the admission level. To the three stages 1, 2, 3 are joined the intermediate coolers I, II, and the 85 aftercooler III which are diagrammatically shown in the form of coils; the normal circuit of the gases is indicated in full line between the different stages 1—2, 2—3 and at the outlet of the stage 3. 90

According to the present invention, there will be admitted at the dead point of the stroke of the piston corresponding to the full expelling or exhaust a small part of the gases which have passed through the intermediate 95 cooler; the flow of these gases in the cylinders is indicated for the three stages 1, 2, 3 by dotted arrows 1a, 2a, 3a, i. e. they enter the cylinders at the dead point of the stroke at the exhaust pressure but cooled. This 100

amount of gas normally cooled by the intermediate aftercoolers at the temperature of suction of the first stage, mixing itself with the compressed gas in the clearance space, 5 noticeably increases the volume thereof while raising the temperature of same but to a small extent. This injected gas expands in the cylinders and its external work is represented by the part covered by hatchings in 10 broken lines, due to the noticeable reduction of temperature during its expansion; it also allows the gas compressed in the clearance space and mixed with the injected gases to supply all of the useful expansion work and 15 the surface covered with hatchings in full lines becomes also useful in this case.

The result thereof is of course a decrease of the useful volume of the cylinder capacity and Figure 1 indicates the proportion which 20 will likely be adopted in practice and which will amount to about 0.7, while it amounts to about 0.9 up to now.

The temperature in the cylinder, during suction, is, due to this fact, sensibly lower 25 than that which corresponds to the outflow from the intermediate cooler and the volume of the cylinder contents or capacity will therefore be better utilized as, for a constant absolute volume, a decrease of specific volume 30 corresponds to an increase in the weight of the admitted gas.

This new system of cooling therefore simply requires the addition of an injection valve which will be controlled from another 35 source and the variable stroke of which will easily allow of varying at will the degrees of cooling.

The cylinder is a simple one, heat-insulated from outside so as to allow under the best 40 possible conditions the complete expansion of the cooled injected gas and of the gas which remains in the clearance space.

As the actual volume of the cylinder is used, with the new system, only to about 0.7 45 instead of 0.9 as stated above, its diameter has to be chosen a trifle bigger. Anyhow its outside diameter, as it is now only a single cylinder, will be less than the outside diameter of the up-to-now standard water-jacketed cylinder.

The inlet valve for the cooled gases being under control, it is still very easy to use one or several short injections of cooled gases during the compression, this representing 55 still a cooling which is much more efficient than the one of the jacketing of the cylinder which has been heretofore universally used.

The entropy diagram of Figure 2 can be briefly explained as follows:— 60 In the ordinary cycle of one stage of a compressor or compressing machine with piston, the suction is effected at the pressure p_0 and the temperature t_0 , specific volume v_0 . The adiabatic compression, i. e. with constant 65 entropy, as far as the pressure p_1 takes place

according to the vertical line drawn in dash and dotted lines and finally comes theoretically to a temperature t_1 and a specific volume v_1 , the intermediate cooling which follows this stage will theoretically return to the same pressure p_1 the specific volume from v_1 to v_4 and the gas will be admitted at this specific volume to the following stage of the compressing machine. 70

The expansion of the gas remaining in the nuisance space at the temperature t_1 and at the specific volume v_1 should take place to attain p_0 at t_0 and v_0 . 75

As indicated above, this however does not occur and the expansion reaches at the pressure p_0 a temperature which is in operation much higher than t_0 and a greater specific volume, which is not indicated in the diagram. 80

According to the present invention, at the dead point at the end of the exhaust stroke, the volume compressed to t_1 , v_1 at the pressure p_1 will have added thereto a volume injected at the temperature t_0 and at the specific volume v_4 , thereby producing a mixture which will always be at the pressure p_1 , at the temperature t_2 and the specific volume v_3 . In virtue of the precautions which are taken, the adiabatic expansion can effectively 90 take place and the pressure p_0 will be attained at the temperature t_4 and the specific volume v_5 . The admission of gas during the suction taking place at the temperature t_0 , before the beginning of the compression, the temperature t_5 and the specific volume v_6 will be attained, so that the adiabatic compression will take place according to the full lines of the diagram and reach p_1 at the temperature t_2 and at the specific volume v_2 . 95

The usual cycle is represented in mixed lines at the places where it does not confound itself with the new cycle, which is represented in full lines. 100

The surface which is hatched inclined to the right above the absolute temperature 0, represents in calories the work of compression to be furnished in accordance with standard practice, a very small part of same having to be deducted for the very small useful work produced by the expansion of the gas contained in the clearance. 110

The surface hatched vertically represents in the same way the work of compression to be furnished in accordance with our invention, but a marked portion of the surface hatched inclined to the left has to be deducted representing the useful work of expansion, of course of a much smaller weight of gas, as the weight of the actually compressed gas. 115

The decrease is visibly an important one and, taking into account the reduction of efficient volume of the cylinder capacity or contents, in the above indicated proportions, there still remains, always to the benefit of the cycle according to the present invention, 120 125 130

an increase of output corresponding to 10% at least.

This new process therefore sensibly improves the outputs which have been up to 5 now obtained, while securing the great simplifications which are above mentioned.

The injection valve can be of any type and is for example constituted, for the first stages, by a balanced valve and for the last 10 stages by a needle-valve.

In the form of construction of compressing machine according to the invention which will be described by way of example, it has been supposed that referred to a two-stage compressing machine, every stage 15 being double acting one.

It is of advantage, to all points of view, to reduce, as regards piston compressors provided with the new system of cooling by 20 injection or back-expansion of cooled gases, the clearance space as much as possible; it is furthermore necessary to reduce to the strict minimum the number of the pieces for the control and of the channels or conduits 25 leading to the ports of the cylinders, as these are precisely the cavities which produce the largest part of the clearance which, anyhow, cannot be practically reduced to zero. The more the number of ports giving directly 30 access to the interior of the cylinder is reduced, the more the leaks which are unavoidable and inherent to every design will be reduced; therefore it is of a great advantage 35 not to increase in any case the number of valves of any system for the use of the back-expansion.

It is very important to give to the exhaust valve a stroke which is as large as possible and considerably greater than the stroke of 40 the automatic spring valves as most generally used at present; it is furthermore possible to combine the exhaust valve with the valve for the inlet of cooled gas, thus having only one valve giving access to the cylinder. The 45 change of communication with the hot gas and cold gas channels can take place behind the exhaust valve, and this combination being quite new, affords the great advantage to reduce in very noticeable proportions the clearance 50 as compared with the actual standard design.

The compressor shown in Fig. 3 comprises two cylinders *a* and *b*, each of them being double acting, with the inlet valves *c* and *d* provided in the cylinder heads and of the automatic type ordinarily in use for the cylinder *a*; and *e*, and *f* for the cylinder *b*; Fig. 3a shows the essential particulars of the suction valve *c* and *c*₁ indicates the seat *c*₂ which is 55 connected by means of the stud *c*₃ with plate-guard and the nut *c*₄ in the standard way to the seat *c*₁. The exhaust valves are *g* and *h* for the cylinder *a* and are provided in the cylinder heads, and *i* and *k* arranged in a similar 60 manner for the cylinder *b*; every case or

box for the exhaust valve is provided with a cylindrical slide valve which is represented at *l* and *m* for the valves *g* and *h* of the cylinder *a*, and at *n* and *o* for the valves *i* and *k* of the cylinder *b*; *p* is the suction pipe leading 70 to the suction valves of the first stage, and *q* the exhaust pipe of this stage leading into the intermediate cooler *r*, into which the cooling water enters through the pipe *s* to leave the same through the pipe *t*. 75

A pipe *u* returns part of the gases cooled by the intermediate cooler to the valve boxes *g* and *h* and the cylindrical slide-valves *l* and *m* connect these valve boxes either with the exhaust pipe *q* or with the return pipe for 80 the cooled gases *u*; *v* denotes the exhaust pipe or conduit of the second stage leading the gases to the aftercooler *w* into which the cooling water enters through the pipe *x* to leave the same through the pipe *y*. The pipe or conduit *z* finally returns part of the cooled gases having passed through the aftercooler to the valve-boxes *i* and *k* and the cylindrical slide-valves *n* and *o* connect the boxes of these valves either with the pipe *v* for the hot gases 85 or with the pipe *z* for the cooled gases. 90

The exhaust valve *g* and the cylindrical slide-valve *l* will now be specially described with reference to Figs. 8 and 9 in which these parts are represented as being moved by an electromagnetic device; the expelling or exhaust valve *g* consists of a valve properly called *a'* made of steel forged into one piece, with its stem *b'*; a sleeve of anti-magnetic metal *c'* avoids, in virtue of its flaring shape, the formation of any eddies above the valve. Following this sleeve *c'*, a sleeve of soft iron *d'* is interposed between the same and another sleeve *e'*; also of anti-magnetic metal which is ended by a piston *f'*; the whole valve forming but a single piece has its weight balanced by a spring *g'*; (this spring is under tension for the valves *g* and *i* provided in the upper heads of the cylinders and under compression for the similar valves *h* and *k* provided in the lower heads of the cylinders). The valve rod moves in a stationary cylinder *h'* made also of anti-magnetic metal forming in its upper part a cylinder *k'* in which the piston *f'* moves; the cylinder and the piston are designed in a known manner 100 so as to act as dash-pots at both ends of the stroke of the valve *g*. 105

The slide-valve *l* is constituted, in its middle part *l* of magnetic metal and in its lower part *i'* and upper part *l'* of an anti-magnetic metal and its weight is balanced by a series of springs *m'* (under tension for the valves provided in the upper heads of the cylinders and under compression for the valves provided in the lower heads of the cylinders). 110

The lower part of the box *n'* as well as the cover *o'* are formed in such manner that the ends *i'* and *l'* of the cylindrical slide-valve *l* 115

automatically form dash-pots at the end of the stroke.

Two coils p' and q' concentric with the axis of the valve can act upon the magnetic circuit r' moreover completed by the soft iron core d' forming one part with the valve g .

Similarly, two coils concentric with the first ones s' and t' can act, through the medium of the magnetic circuit u' upon the middle part l of the cylindrical slide-valve made of magnetic metal; the starts and ends of the coils, represented at v' and w' cross the covers through insulators x' and y' . Figs. 8a and 8b being a cross section according to A—A of Fig. 8a represent one of these insulators. Each carries four wires V_1 which are embodied in insulating material V_2 . A metallic sleeve V_3 in two pieces is held on by a conical one-piece sleeve V_4 also made of steel. The whole is secured into the insulating cylinder V_5 by means of the nut V_6 , the cylinder itself being fixed in the casing by the nut V_7 pressing on the tightening ring V_8 and secured itself by the additional nut V_9 . Finally the dotted position z' shows the valve as being lifted from its seat and the passage with a very large cross section afforded to the gas entering and leaving the cylinder; the inlets and outlets of the pipes u and q are also indicated in Fig. 8 and the flow marked by corresponding arrows.

By exciting either the one or the other of the coils p' or q' and s' or t' , the valve g and the slide-valve l will be either at the bottom, or the top end of the stroke; it is easy to understand that by reasonable choice of the working data, it is possible to impart to the two valves a relatively large stroke with a very small consumption of power whereas their weight is completely balanced and their inertia is very small. Through the periodic excitation either of the lower or of the upper coils, very quick motions both of the exhaust valve g and of the cylindrical slide-valve l will be obtained. Fig. 8 shows the two closing devices in the lower position, the valve g closing the interior of the cylinder and the cylindrical slide-valve l giving access to the cold gases, through the pipe u , to the valve box.

Fig. 10 shows for two revolutions of the crank-shaft the motions of the cylindrical slide-valve which takes place at the dead points. The hot gases have access to the box of the valve g during all the exhaust stroke. At the dead point of the suction stroke, the slide-valve effects the downward stroke and allows, for all this stroke, cold gases to have access to the box of the exhaust valve; at the next dead point between the suction and exhaust stroke, this slide-valve is lifted and again gives access to the hot gases.

Fig. 11 shows the motion of the exhaust valve a' in a similar manner in function of

the time and for the same two full revolutions of the crank shaft, its up and down strokes; the ascending stroke during the exhaust stroke of the piston corresponds to the point at which the pressure of operation is attained in the cylinder, the same being followed by the period of exhaust of the hot gases in to the intermediate cooler; the closing of the valve sometime after the dead point of the beginning of the suction stroke stops the reintroduction of the cold gases at the same pressure into the cylinder, in order to start the useful expansion for work and for cooling of the gases then contained in the cylinder.

To complete the showing of the motions of the valve, Fig. 12 gives the opening of the suction valve c , d , e or f , and the duration of its automatic opening during the suction stroke after the gases effecting the back-expansion will have expanded at the suction pressure, and its closing at the dead point between the suction and exhaust stroke.

The mechanism, such as it is represented, therefore allows to carry out in a very simple manner the principle of the back-expansion according to the invention with a minimum of shutting off devices giving access to the interior of the cylinder as the usual automatic exhaust valve with a very small stroke and consequently a very large diameter, or even an annular one with several rings, is replaced here by a single valve with a big stroke, acting at the same time as a valve for the reintroduction of the cold gases at the beginning of the suction stroke of the piston. The speed of the movements of the exhaust valve for back-expansion, on the one hand, and of the cylindrical slide-valve, on the other hand, is higher, than with any other either mechanical or hydraulic drive. Finally this drive through electromagnets allows to provide for a complete closing of the exhaust valve box and therefore prevents in an absolute manner every loss of gases, which would not be the case with a mechanical or hydraulic drive of the said valve the former one necessitating a stuffing box and the latter giving the possibility of a mixture of the gases with the inevitable leaking of oil.

It remains to describe the valve controlling mechanism which is represented in Figures 3 to 7.

The crank-shaft A carries a toothed wheel B which drives at the suitable rate a dynamo C supplying the direct current for periodically exciting coils of the electromagnets. By means of spur gear wheels, D, E and F, the two driving shafts G and H parallel to the crank-shaft A move in a reverse direction the one to the other; the shaft G moves clockwise and the shaft H moves counter clockwise for an observer placed at the end of the compressor on the side of this drive. The shaft G carries an eccentric I which is

shown diagrammatically in Fig. 5 and in a substantial arrangement in Fig. 6; this eccentric is connected with a rod K the left end of which moves in a slideway or guide 5 while its right end M describes a curve in the direction of the arrow X¹. Fig. 6 shows four main positions of the eccentric I and the parts of the curve N described by its end M.

The shaft H carries in a similar manner 10 eccentric O which causes a curve P to be described in the direction of the arrow X² by the end Q of the eccentric rod O the right end R of which moves in a guide S. The two ends M and Q of the eccentrics I and O 15 act upon a switch or interrupter with 3 mercury contact electrodes in the empty space represented at T and at the upper part of the curves N and P, the ends M and Q cause the said switch T to rock in the one or in the other direction. In one position, it closes the circuit on one of the coils of the electromagnet and in the other position the other magnet for the same member to be operated.

Under the action of the screws U and V, 20 the slides S can, as shown in Fig. 7, assume different positions thereby raising or lowering in space the curves described by the ends M and Q of the eccentric rods this enabling to easily control the moments of energizing 30 and de-energizing of every coil provided in the exhaust valve box.

This mechanism therefore allows to regulate at will the play of motion of the exhaust valves for the back-expansion, on the one hand, and of the cylindrical slide-valve, on 35 the other hand.

It is moreover easy to adjust the same while the compressor is in operation and this adjustment can moreover be automatically 40 made dependent upon the exhaust pressure at the last stage of the compressor, in order to control the cooling of the cylinders even when working under conditions of disturbance so as to maintain, if desired, as perfect 45 as possible permanent balance of the work of the different stages of the compressor adapted to operate under exhaust pressures capable of varying in large proportions.

In order to reduce the effect of retardation 50 of the energy of the switching in and cutting out currents in the electric circuits, the energy of these currents will be absorbed, as usually done, by resistances connected in series, or by combinations of resistances and 55 of capacities.

It will be understood that the drawing only shows by way of example the principle 60 which consists in combining the exhaust valve with the valve for the reintroduction of the cold gases and with the device for reversing the communications of the hot gases and the cold gases with the box of the said valve; the intrinsic advantages of the drive by electromagnets have moreover been exposed in this description, but the delivery

or distributing parts can also be operated by mechanical or hydraulic driving devices and even also by other systems of electric drive.

Having thus described my process and apparatus, what I claim as new therein, and 70 my own invention, is:—

1. In a piston compressor with intermediate and after-cooler, the combination of a cylinder with compression piston, a cooler, a box on said cylinder and two pipes connecting 75 said box, the one with the inlet of the said cooler and the other with the outlet of the same cooler, an inlet valve for the admission of the gas to be compressed in the cylinder, an exhaust valve connecting the cylinder 80 with the said box and a valve provided for alternatively closing one of the two mentioned pipes, means for controlling the last two valves and adapted to open the communication of the said chamber with the outlet of 85 the cooler at the end of the exhaust stroke during the admission stroke, and at its end the closing of the exhaust valve.

2. In a piston compressor with intermediate and after-cooler, the combination of a 90 cylinder with compressing piston, a cooler, a cylindrical box on said cylinder and two pipes connecting this box, the one with the inlet of the said cooler, and the other with the outlet of the same cooler, an inlet valve for 95 the admission of the gas to be compressed into the cylinder, an exhaust valve between the cylinder and the said box, a cylindrical slide-valve sliding in this box, electromagnetic devices enclosed within the said box for 100 controlling or driving the exhaust valve and the slide valve, exciting means for the purpose of sending exciting currents into the said driving devices, the said exciting means being so connected as to remove the slide- 105 valve at the end of every piston stroke and to open the exhaust valve during the last part of the expelling stroke and the first part of the admission stroke.

3. In a piston compressor, a cylinder provided with an after-cooler, a box on said cylinder, a discharge valve connecting the cylinder with the box, separate means connecting the box with the inlet and the outlet of the intermediate and after-cooler, and a slide 110 valve alternately opening and closing said 115 separate means.

4. In a piston compressor, a cylinder provided with an after-cooler, a box on said cylinder, a discharge valve connecting the cylinder with the box, separate means connecting the box with the inlet and the outlet of the intermediate and after-cooler, and a slide valve alternately opening and closing said 120 separate means and electromagnetic means 125 for controlling the slide valve and the discharge valve.

5. In a piston compressor, a cylinder provided with an after-cooler, a box on said cylinder, a discharge valve connecting the cyl- 130

inder with the box, separate means connecting the box with the inlet and the outlet of the intermediate and after-cooler, and a slide valve alternately opening and closing said 5 separate means, and electromagnetic means for controlling the slide valve and the discharge valve, a contact device controlling said electromagnetic means, and means for adjusting said electromagnetic means.

10 In testimony whereof I have hereunto affixed my signature.

ALBERT HUGUENIN.
